UNITED STATES PATENT OFFICE.

JAMES H. SHEAHAN, OF FREEPORT, ILLINOIS.

WATER-MOTOR.

1,111,722.

Specification of Letters Patent.

Patented Sept. 22, 1914.

Application filed November 16, 1910. Serial No. 592,633.

To all whom it may concern:

Be it known that I, JAMES H. SHEAHAN, a citizen of the United States, residing at Freeport, in the county of Stephenson and State of Illinois, have invented a certain new and useful Improvement in Water-Motors, of which the following is a specification.

This invention relates to water motors, and has for its object to provide a new and improved device of this description.

The invention is illustrated in the accompanying drawings, wherein—

Figure 1 is a sectional view showing the parts in position; Fig. 2 is an enlarged sectional view through the lower end of the chamber into which the shaft of the water motor projects; Fig. 3 is a view of the propeller blades and associated parts; Fig. 4 is an end view of a modified construction.

Like numerals refer to like parts throughout the several figures.

In the present case there is shown a water motor adapted to be used at all times of the year, and arranged so that the forming of ice on the water does not in any manner interfere with its operation.

Referring now to the drawings, I have shown a propelling device provided with propeller blades 1 and 2. These propeller blades are connected to a shaft 3, rotatably mounted in a frame 4 having side pieces 5. Extending around the shaft 3 and the propeller blades 1 and 2 is a concentrating device adapted to concentrate the water upon the propeller blades. As herein shown this concentrating device consists of a strip of material 6 formed into a spiral shape, having one edge nearer the shaft than the other edge. This concentrating device may be termed an inclined spiral, as it is a spiral with the convolutions inclined. This inclined spiral is formed by cutting out a strip of material with one edge shorter than the other so that when it is formed in the spiral one edge will be nearer the shaft than the other, as illustrated. This concentrating device is fixed with relation to the propeller blades, that is to say, it is held in position so that it does not rotate. This may be accomplished in any desired manner, as by fastening the edges to the side pieces 5, as shown in Fig. 3, by means of the bolts or screws 7.

In the operation of the device the water is flowing in the direction of the arrow in

Fig. 1, and it will therefore be seen that the various convolutions of the inclined spiral direct or concentrate this water upon the propeller blades. The side pieces 5 may be of buoyant material if desired. In cases where the device is to rest upon the bottom of the stream I may provide the shaft and propeller blades with the frame shown in Fig. 4. This permits the propeller blades to be held free from the bottom regardless of the position of the device. The shaft 3 is connected with a shaft 8 which extends into a receptacle 9. This connection may be made in any desired manner, but is preferably a universal joint connection, made by an intermediate shaft section 10 and the universal joints 11, 12. The receptacle 9 may be made in any desired manner, and is preferably watertight, and extends above the surface of the water so that it can be kept free from water at all times. The shaft 8 preferably extends through a suitable stuffing-box 13. An operative driving connection is provided between the shaft 8 and the driven device which may be located upon the shore or at any other desired point. As herein shown the shaft 8 is connected by suitable beveled gears to the shaft 14, which is connected by suitable beveled gears to the shaft 15, extending to the driven device on the shore.

In order to insure the receptacle 9 being kept free from water, I prefer to provide a suitable pump, arranged so that it will pump water out of the receptacle. I also prefer to make this device automatic, so that when the water reaches a predetermined height the motor will be connected with the pump so as to pump the water out of the receptacle 9. As herein shown, I provide at the bottom of the receptacle a sump 16, in which the water collects. Located in this sump is a bucket 17 suspended from a pivoted support 18. As herein shown this pivoted support is pivoted to the bracket 18^a carrying the bearing for the shaft 14. At the other end of the pivoted support is a balancing weight 19.

Carried by the support 18 is a wheel 20, adapted to be brought into contact with the wheels 21 and 22. The wheel 21 is on the driving shaft 8, and when wheel 20 is in contact with wheels 21 and 22 it will be noted that the wheel 22 will be driven. The wheel 22 when it rotates operates a pump 23 which pumps water out of the bucket 17. This

pump 23 is preferably stationary, and may be supported by a bracket 24. The pump is preferably provided with a flexible suction pipe 25 and with a discharge pipe 26, which extends through the wall of the receptacle 9. This discharge pipe may be arranged in any other desired manner.

In the operation of the device the water first collects in the sump. As the bucket is 10 empty, the bucket will float on this water, and will be lifted so as to disengage the wheel 20 from the wheels 21 and 22. After a certain amount of water accumulates in the sump the lifting of the bucket will move the 15 support 18 so that the weight 19 rests upon the bottom of the receptacle. The upward movement of the bucket is now stopped, and as the water rises in the sump it will reach the top of the bucket and flow into the bucket. When a predetermined amount is 20 in the bucket, the bucket will sink and will bring wheel 20 into contact with wheels 21 and 22. This starts the pump 23, which then pumps water out of the bucket. After 25 the water in the sump is lowered to the top of the bucket the further pumping lowers the water in the bucket, and when the height of the water in the bucket reaches a predetermined amount, depending upon the size 30 of the weight 19, the bucket will be floated by the water, and the weight 19 will move the support 18 so as to disconnect the wheel 20 from wheels 21 and 22 and stop the pump.

The operation above described will be repeated automatically when the water reaches a predetermined height in the sump.

I claim:

1. A water power apparatus comprising a shaft, propeller blades thereon adapted to be 40 acted upon by the current of water, so as to rotate said shaft, and an inclined spiral disconnected from said shaft and extending around said propeller blades.
2. A water power device comprising a receptacle extending above the surface of the 45 water and fixed in position, a shaft therein

extending through the wall of the receptacle, a rotating device actuated by the current operatively connected with said shaft, so as to drive the same, a water-removing device located at the bottom of said receptacle, and means in said receptacle for automatically connecting it with said shaft when the water reaches a predetermined height in the receptacle.

3. A water power device comprising a rotatably mounted shaft, propeller blades connected therewith, an inclined spiral surrounding said shaft and propeller blades and fixed in position with relation to said 55 shaft.

4. A water power device comprising a rotatably mounted shaft, propeller blades connected therewith, an open spiral surrounding said shaft and propeller blades, and an 60 outer frame to which said spiral is connected so as to be held against rotation.

5. A water power device comprising a receptacle extending above the surface of the water and fixed in position, a shaft therein 70 extending through the wall of the receptacle, a current actuated rotating device outside of the receptacle and operatively connected with said shaft, so as to drive the same, a pump in said receptacle, a pivoted lever in said receptacle, a weight at one end of said lever, a bucket at the other end of said lever, a suction pipe for said pump in said bucket, and means for automatically connecting the pump with said current actuated device when the water reaches a predetermined height.

6. A water power device comprising a propeller adapted to be rotated by the current of water and an open spiral surrounding said propeller.

Signed at Chicago this 24th day of October, 1910.

JAMES H. SHEAHAN.
